J. M. THOMPSON
GATE SUPPORTING MEANS

Filed March 20, 1926

Inventor,
John M. Thompson,

G. Kennedy
by
Attorney.

Patented Feb. 8, 1927.

UNITED STATES PATENT OFFICE.

JOHN M. THOMPSON, OF THORPE, IOWA.

GATE-SUPPORTING MEANS.

Application filed March 20, 1926. Serial No. 96,305.

My invention relates to improvements in gate supporting means, and the object of my improvement is to support a swinging gate for vertical adjustable elevation as desired, 5 with means for retaining it releasably in any adjusted position.

It is to be understood that this invention may be utilized for any descriptions of swinging gates, doors or closures for which 10 it may by modifications be applicable, and that changes in the proportions, dimensions, arrangements and minor details thereof are nevertheless covered by the claims herein.

I have accomplished the above object by 15 the means which are hereinafter described and claimed, and which are illustrated in the accompanying drawings, in which Fig. 1 is a front elevation of a swinging gate supported for adjustable vertical elevations according 20 to my invention. Fig. 2 is a view of the rear post and vertical movable standard, partly in rear elevation and partly in central vertical transverse section, parts being broken away. Fig. 3 is a detail view, showing parts 25 of the device in horizontal section and other parts in top plan.

The numeral 1 denotes a base-beam to be mounted fixedly upon or embedded in a supporting surface, whether of the soil or otherwise 30 and across an opening, as in a fence or building.

Base-plates 2 spaced apart and located near the ends of said beam are fixed thereto upon its upper surface by any suitable 35 fastening devices. Instead of the beam 1, any other desired fixed support may be supplied instead, as concrete blocks or the like.

The numerals 3 and 29 denote respectively 40 the rear and front gate-posts which are integral with or fixedly mounted on the base-plates 2 near the ends of the beam 1. The rear post 3 is tubular and a coiled compression spring 4 is mounted in the lower part of its hollow to rest terminally upon the 45 plate 2. A cylindrical standard 5 is slidably and loosely fitted within the post 3 and has its lower end supported upon the upper end of said spring 4. The standard 5 projects above the upper end of said post 3, and 50 is bent reversely downwardly parallel to the vertical post 3 to supply a depending part 7, and the parts 5 and 7 are tightly clamped together near said bend by a split clamping body 8 and bolt to thus stiffen and support 55 the parts 7 parallel to the part 5 and the post 3. A split clamping device 9 with

through bolt 10 is tightly clamped upon the lower end of said part 7 and is loosely connected with the post 3. The upper end of the post 3 is at 11 widened to support a split 60 clamping body 12 as shown in Fig. 3 loosely mounted upon an inner sleeve 13 around and loose on the standard 5 but secured by threads 14 to the top of said post 3, with its annular head resting on the body 12. 65 The body 12 is loose upon the standard part 7 also. Like split clamping devices 22 and 23 are by like bolts 21 clamped tightly upon the standard part 7, spaced vertically, and upon the rear stile 24 of a gate 25 mounted to 70 span the interval of the posts 3 and 29. The standard 5 may rock in the post 3 carrying with it and its part 7 the gate 25 to be swung open or closed.

The gate may be of any desired construction, whether rigid or flexible. As shown it has an endless tubular frame with rear and front stiles 24 and 28. Any desired catch may be used to releasably fasten the front stile 28 to the front post 29, and I have 80 shown a spring arm 30 secured on this post to project upwardly and carries a troughed head 31 to partially embrace the stile 28 when the part 30 is untensioned.

The parts of the gate frame may be connected by wires crossed or connected together as at 26, or otherwise.

The forward end of the gate is braced by a rod 27 connected to the forward part of the gate frame and to the standard 90 part 7 above the clamping body 8.

I have furnished means for releasably securing said gate in any desired position of vertical adjustment within limits, upon said post 3. This means comprises a headed bolt 95 15 traversing aligned apertures in the clamping-body 12 between the standard parts 5 and 7 transversely with its threaded end projecting and having a cylindrical block 32 mounted rotatably in mesh thereon and therewith. The opposite ends of this block 32 serve as pintles for the apertured furcations 19 of a lever having a diminished handle part 20. The edges of the furcations are shaped with like opposite cams 18 and intermediate cam parts of less radius. A short coiled compression spring 16 is mounted on the stem of said bolt 15 in contact with the body 12, and a washer 17 is also mounted on said stem between and in contact with said 100 spring and with the cam edges of the furcations 18.

By turning the lever 20 around the threaded stem of said bolt 15, more or less compression may be applied to the spring 16 as may be necessary.

5 When the lever 20 is lifted as shown in Fig. 3 to a horizontal position, with the cam edges of less radius bearing upon the washer 17, the spring 16 is so relaxed that the clamping device 9 may slide upwardly 10 upon the post 3 by the reaction of the previously compressed spring 4 to any desired elevation or until stopped by the contact of the upper clamping device 22 with the clamping body 12, the standard part 5 15 moving upwardly in the hollow of the post 3. When the gate is in the desired position of elevation relative to the said post 3, the lever 20 may be swung downwardly to cause the cam edges 18 of greater radius to 20 push over the washer 17 to so compress the spring 16 as to clamp it against the body 12 while drawing upon the bolt 15 to thus clamp the split end parts of the body 12 upon the standard member 7, so that the latter 25 together with the gate are held at the desired elevation. At this elevation the gate may swing over obstacles such as snow drifts below, or afford clearance so that small animals may pass beneath it while 30 larger animals are barred.

The cams may be turned to release the standard part 7 in the clamping device or body 12, and the operator then by foot pressure upon the lower longitudinal member 25 of the gate frame push down the gate to lower it to an adjusted or to its lowermost position, and then swing the lever downwardly as shown in Fig. 2, to re-clamp the part 7 to the body 12. The spring 16 when 40 the lever 20 is swung upwardly, helps to carry the weight of the lever in reacting.

It will be seen, that in any position of adjustment relative to the post 3, the gate may be swung freely to and fro, and without interference with the lever and its cams 20—18, and as the cams are at or a little past the dead center when the lever is down, the gate is locked in its vertically adjusted position upon said part 7.

50 Having described my invention, what I claim as new, and desire to secure by Letters Patent, is:

1. In combination, a fixed support, a tensionally controlled member movable vertically relatively to and also swingingly movable upon said support, a gate secured upon said member, and tensionally controlled means for releasably holding said member in a vertically adjusted position upon said support while permitting the member and the gate to swing horizontally freely relative to the support.

2. In combination, a fixed support, a tensionally controlled member movable ver-

tically relatively to and also swingingly mounted upon said support, a gate secured upon said member to swing therewith horizontally, and means for releasably holding said member and gate in a vertically adjusted position upon said support while permitting the member and gate to swing freely, said means including a tensionally controlled cam device operative to releasably adjustably secure said member to the support at or past the dead center of the cam and means for adjusting the cam of said device toward and from said member.

3. In combination, an open top tubular post, a coiled compression spring within said post, a standard mounted slidably and rotatably within the hollow of said post and supported upon said spring, the upper part of said standard projecting upwardly from the post and bent reversely to have a depending part adjacent the post, clamping bodies rotatably non-slidably connected to the post and slidably connected to the pendent part of said standard, a gate mounted upon the said pendent part of said standard, a threaded stem bolt traversing aligned apertures in said clamping bodies, and a cam device rockingly mounted upon said threaded stem adapted to compress the bodies in one position of the cam thereagainst upon said pendent part to hold the same and the gate in a vertically adjusted position relative to said post.

4. In combination, an open top tubular post, a coiled compression spring within the hollow of the post and having its lower end stopped, a standard mounted slidably and rotatably within the hollow of the post and supported yieldingly upon said spring, the upper part of said standard projecting upwardly beyond the top of the post and being bent downwardly reversely, clamping bodies rotatably non-slidably mounted upon the post and slidably loosely connected to the pendent part of said standard, a gate mounted rigidly upon said pendent part, a bolt traversing aligned apertures in said clamping bodies, a cam mounted for rocking adjustment on said bolt, having like opposite cam edges of greater radius than the intermediate edge of the cam, a coiled compression spring mounted on said bolt between said cam and said clamping bodies, and said cam being rockable relative to said spring and clamping bodies to either compress the spring to clamp the said bodies upon said pendent part tightly and hold the same fixed when the cam is at or past a dead center, or to release the same to permit the clamping bodies to be loose upon said pendent part.

In testimony whereof I affix my signature.

JOHN M. THOMPSON.
